UNITED STATES PATENT OFFICE.

RICHARD R. THOMAS, OF INDIANAPOLIS, INDIANA.

GARMENT-SUPPORTED TOOL-CARRIER.

1,354,926.

Specification of Letters Patent.

Patented Oct. 5, 1920.

Application filed May 5, 1920. Serial No. 379,114.

To all whom it may concern:

Be it known that I, RICHARD R. THOMAS, a citizen of the United States, residing at Indianapolis, in the county of Marion and State of Indiana, have invented a new and useful Garment-Supported Tool-Carrier, of which the following is a specification, reference being had to the accompanying drawings and to the letters and figures of reference marked thereon.

This invention relates to a holder that is designed to be connected to a workman's garment, more particularly to his overalls, to carry a frequently-used tool, for example a paper-hanger's shears, the invention having reference more particularly to a tool carrier that is designed to permit a tool to be quickly and readily placed in it without requiring observation of the workman, and also permitting the tool to be readily reached and withdrawn for use.

An object of the invention is to provide a tool-carrier which shall be so constructed as to be capable of being firmly secured to a garment, such as overalls, and which may be further supported if desired by the workman's belt when a heavy tool is to be carried. Another object is to provide a tool-carrier which shall be especially adapted for carrying long shears such as used by paper-hangers, and which shall be of simple and inexpensive but strong and reliable construction. A further object is to provide a tool-carrier which shall be so constructed as to be dependable, easily operated and permit the workman to mechanically place his shears therein or to remove them therefrom while his eyes are directed to the work in hand. A still further object is to provide an improved garment-supported tool-carrier which shall be of such construction that it may be arranged to carry the shears or other tool in hanging position on the workman's overalls without being obstructive or causing the tool to interfere with free movement of the workman on a ladder, which carrier shall be durable and economical in use.

With the above-mentioned and other objects in view, the invention consists in a tool-carrier having certain novel features of construction whereby improved results are obtained in use; and, the invention consists also further in the novel parts or features, and in the combinations and arrangements thereof, as hereinafter particularly

described and further defined in the accompanying claims.

Referring to the drawings,—Figure 1 is a front elevation of the improved tool-carrier; Fig. 2 is a perspective view of the tool-carrier represented as being connected to a workman's garment and further supported by the workman's belt, and illustrating a paper-hanger's shears in the carrier, the garment and the belt and also the shears being shown by broken lines; Fig. 3 is a top view of the improved carrier; Fig. 4 is a top view of the carrier and shear blades in transverse section arranged as when the shears are being inserted in the carrier; Fig. 5 is a transverse vertical section of the carrier; and, Fig. 6 is a fragmentary detail of associated parts of the carrier.

Similar reference characters in the different figures of the drawings indicate corresponding elements or features of construction herein referred to in detail.

In the drawings the numeral 1 indicates the clothed body of the workman, 2 the workman's overalls and 3 the workman's belt; and 4 and 5 indicate shear blades, 6 the larger handle eye and 7 the smaller handle eye of the shears which the carrier is more particularly designed to accommodate. As preferably constructed the carrier comprises a base plate 8 designed to be arranged uprightly against the workman's right leg or thigh and it has a concave lower right-hand edge portion 9 so that an upper guide extension 10 is formed of less depth than the body portion of the plate, the extension being curved rearwardly to approximately fit to the leg. At the left-hand side or edge of the base plate it has a rearwardly curved guide extension 11 at the upper portion of the plate. The carrier has a sheath member comprising a curved base portion 12 extending from the plate 8 below the extension 11 to support the handle eye 6 of the shears, and a front portion 13 extending from the portion 12 and divergently with respect to the plate 8. The curved portion 12 of the sheath has an outwardly extending flange or bead 14 at its top to afford ample surface for supporting the shear handle and to also stiffen the curved portion. The main portion of the sheath extends downward a suitable distance toward but not as far as the lower edge of the plate 8, and a portion of its top edge 110

13' extends along the plane of the top of the curved portion 12. The lower right-hand portion of the sheath member is cut away so as to form a concave edge 15 and 5 to leave a relatively narrow extension 16, the top edge 17 of which is higher than the top edge 13'. The extension 16 has a hinge member 18 integral therewith which extends from the top edge 17 downward to 10 ward but not as far as the lower edge of the extension so that a recess 19 is formed for a purpose which will become apparent. An arm 20 is provided which has a right-angled shaft 21 thereon which is rotatively ar- 15 ranged in the hinge member and extends downward through it. The arm 20 has a locking-bar 22 on its end which extends forwardly at an obtuse angle relatively to the arm, and the end of the bar preferably has 20 a downward extending stop finger 23 thereon to engage the front of the sheath member, the locking-bar extending over the top of the member and may be partially supported thereon so as to afford a support for 25 the handle eye 7 of the shears when the arm 20 is held in contact with the plate 8. The lower end of the shaft 21 has a slot 24 therein, a coil spring 25 is arranged on the projecting portion of the shaft and masked 30 in the recess 19 so as to not be obstructive, and the spring has one arm 26 extending into said slot and another arm 27 in contact with the back of the extension 16 below the hinge member 18. The base plate 35 is provided with a suitable number of pins for detachably securing it to the workman's garment, there being preferably three pins so as to firmly secure the carrier in place and prevent it from tilting. The securing 40 pins may be variously constructed but preferably comprise base rods 28, 29 and 30 respectively, which preferably are passed through loops 31, 32 and 33 respectively, which are pressed from the metal of the 45 carrier base, one being adjacent to the extension 11 and another in the extension 10; and pointed pins 34, 35 and 36 are formed integral with the base rods respectively, the lower portion of each base rod having 50 a catch 37 formed thereon to retain the adjacent pin. The lower portion of each base rod preferably is secured to the base plate by means of solder 38.

55 Preferably the upper portion of the base plate 8 has a horizontal slot 39 therein to receive a supporting strap 40 which has a loop 41 to receive and be supported by the belt 3.

60 In practical use, the carrier being in position as described, the spring 25 holds the arm 20 with slight pressure against the plate 8. The workman holding the shears thrusts the blade sidewise against the arm 20 which is swung away from the plate 8 by 65 the shear blades, the blades sliding against

the arm until passed beyond the arm, the arm being retracted by the spring 25, after which the workman, as he feels the shears striking the curved portion 12, drops the shears into place and proceeds with his 70 work, the locking-bar 22 preventing the shears from falling away from behind the sheath member. When the workman again needs the shears he can readily find the handles and withdraw the shears from the 75 carrier, being permitted to readily pull them upward therefrom. As the workman moves about, the shears hang securely in the carrier and the well supported handle eyes prevent them from tilting about and becoming 80 obstructive.

Having thus described the invention, what is claimed as new is—

1. A tool-carrier including a base plate, a sheath member extending from the base 85 plate and having an end extension and a top extension, the sheath member having a bead on its top adjacent to the base plate, an arm having a shaft rotatively supported by the end extension and having also a locking bar 90 thereon guided upon the top extension of the sheath member, the shaft terminating adjacent to the lower edge of the extension, and a spring connected with the shaft of the arm adjacent to its end and also with the 95 end extension of the sheath member.

2. A tool-carrier including a base plate having rearwardly-curved extensions on the upper portions of the two opposite ends thereof, the plate having a sheath member comprising a forwardly-curved base portion extending from an end of the base plate below one of the extensions thereof and a front portion extending from the base portion, the curved base portion having a flange 105 extending outward from the top thereof, said front portion having an end extension, the upper portion of the end extension having a hinge member thereon, a locking arm having a shaft rotatively supported by said hinge member and having also a bar on its end that extends across the top of said extension and has a downward extending short projection on its end, the lower end of said shaft having a coil spring thereon, the 110 spring having an arm connected to the shaft and an arm engaging said end extension, and a plurality of pins secured to the upper portion of the back of the base plate.

3. A tool-carrier including a base plate 115 having rearwardly-curved extensions on the upper portions of the two opposite ends thereof, the upper portion of the plate having a slot thereon to receive a hanger, the plate having also a sheath member comprising a forwardly-curved base portion extending from an end of the base plate below one of the extensions thereof and a front portion extending from the curved base portion, the curved base portion having a flange ex- 120 125 130

tending outward from the top thereof, said front portion having an end extension and a top extension, the upper portion of the end extension having a hinge member thereon,
5 a locking arm having a shaft rotatively supported by said hinge member and having a bar on its end that extends across the top of said top extension and has a downward-extending projection on its end, the
10 lower end of said shaft having a slot therein, a coil spring on said shaft and having an

arm secured in said shaft slot and an arm engaging said end extension, and a plurality of securing pins mounted on the back of said base plate.

15

In testimony whereof, I affix my signature in presence of two witnesses.

RICHARD R. THOMAS.
